UNITED STATES PATENT OFFICE.

JOHN N. HAHN, OF CLEVELAND, OHIO.

MACHINE FOR FACING CORRUGATED PAPER.

1,015,385.

Specification of Letters Patent.

Patented Jan. 23, 1912.

Application filed September 28, 1910. Serial No. 584,215.

To all whom it may concern:

Be it known that I, JOHN N. HAHN, citizen of the United States, residing at Cleveland, in the county of Cuyahoga and State 5 of Ohio, have invented certain new and useful Improvements in Machines for Facing Corrugated Paper, of which the following is a specification.

My invention relates to machines for facing corrugated paper, and the invention resides in the construction and arrangement of parts substantially as herein shown and described and more particularly pointed out in the claims. In machines of this kind the 10 facing paper, also called the backing, is attached to the corrugated paper by an adhesive, and pressure and heat are required to obtain a perfectly smooth and uniform product. At best the operation of drying is 15 generally slow and the output for a predetermined time limited although continuously carried on.

One of my objects is to greatly increase the output of a single machine as compared 20 with other apparatus used heretofore, and at the same time reduce the size of the machine, economize in floor space and fuel consumption, and otherwise improve such apparatus to make an acceptable product.

30 In the accompanying drawings, Figure 1 is a side elevation of two rolls of corrugated paper and two rolls of facing paper and the adhesive-applying devices of the machine, and Fig. 2, Sheet 2, is a side elevation on the 35 same scale, of the feeding, drying and pressing parts of the machine. Fig. 3 is a plan view of that part of the machine shown in Fig. 2, but partly sectioned away on a horizontal line corresponding to line 3—3, Fig. 4. Fig. 4 is a cross section on line x—x, Fig. 2, but enlarged as compared therewith. Fig. 5 is a diagrammatic view showing the 40 relative arrangement of the various rollers for guiding the corrugated paper and facing paper through the adhesive-applying devices to back two separate corrugated strips simultaneously and in a continuous manner.

As shown, this machine is primarily 50 designed to face only one side of a corrugated strip of paper, or straw board as it is usually called. To increase the output however, the machine is particularly constructed to duplicate said facing operation on two 55 strips 2 and 3 taken from two rolls A and B, respectively, both strips being faced simul-

taneously as they are fed forward conjointly by the same mechanism. Furthermore corrugated strips 2 and 3 are shown as coming to the machine with one side already faced or backed by a plain sheet of paper. This is the preferred manner of operating, but I wish to state that I can also use this same machine to single-face a single corrugated strip,—one that has no facing-sheet on either side originally, or double-face a single corrugated strip. Single-facing and double-facing of two corrugated strips simultaneously may also be easily accomplished, but in these modified operations, the feed of the strips and the facing sheets would have to be re-arranged more or less to apply the adhesive properly.

60 *The supply rolls.*—Roll A is wound in such manner that the corrugated side of the strip 2 is delivered uppermost, or as it appears in the roll with the corrugated portion *a* on the outside and with facing-sheet *b* already affixed on the inside. On the other hand, strip 3 of roll B is wound differently so that a reverse effect is obtained as to its two sides, or in other words, strip 3 is wound on the roll with its attached facing-sheet *b* on the outside to deliver the flat side of the strip uppermost. This permits 65 rolls A and B to be placed in line one in advance of the other and the flat side *b* of strip 2 fed forwardly in contact with the flat side *b* of strip 3. These rolls are necessarily bulky and heavy and when exhausted 70 must be replaced. Therefore both rolls are 75 rotatably mounted upon independent trucks or wheeled supports 4 which may be conveniently handled and shifted from place to place and finally located in line with the 80 machine. When this is done, strip 2 of roll A is fed forwardly over roll B and rests upon the same, and strip 3 unrolls and is 85 fed forward at the same speed as strip 2 during succeeding operations.

90 *The adhesive-applying device.*—Referring to Figs. 1 and 5, strips 2 and 3 pass from the rolls in substantially parallel lines to and beneath separate idler rollers 5 and 6, respectively, mounted in suitable bearings in 95 frame or table 7. Two adhesive-applying devices 8 and 9 are supported on top of table 7, one in advance of the other, and strip 2 travels upwardly from roller 5 at an inclination and passes around a roller 10 100 and thence to the rear on a horizontal line above glue pot 8 and in contact with glue-

applying roller 11 and idler roller 12 above the same. This arrangement inverts the corrugated face of strip 2 in its travel so that corrugated portion *a* will receive the adhesive; then said strip makes a turn about another roller 14 which again places the corrugated side upon top to receive facing sheet *c* fed from a roll C mounted rotatably in brackets 15 on table 7. Primary union 10 between sheet *c* and strip 2 is effected by feeding said strip and sheet conjointly between a pair of rollers 16 and 17, also mounted in suitable brackets 18 located on table 7 at an intermediate point between devices 8 and 9. Strip 3 also passes between rollers 16 and 17 with the flat side *b* thereof in contact with the flat side *b* of strip 2. From this point both strips are fed forwardly in a straight line and in contacting 15 relation and pass between glue-applying roller 19 and its co-acting idler 20 of device 9, and it will be noted that corrugated portion *a* of strip 3 is on the bottom to receive the adhesive from roller 19. The next 20 step in operations involves attachment of a facing sheet *d* to strip 3 and this is accomplished by feeding a plain paper sheet of the requisite thickness from a roll D corresponding to roll C but located at a lower 25 elevation beneath the line of feed of said strips, floor standards 21 being used to removably support said roll D. The sheet passes from this roll around an idler roller 22 on table 7 and thence upwardly and 30 around a roller 23 mounted in open brackets secured to device 9. A partial union between the adhesive surface of sheet *d* and the corrugated portion *a* of strip 3 is effected when said parts come into contact at 35 roller 23. However, both strips 2 and 3 are unfinished at this stage in operations although each strip is now doublebacked. To finish the same the next essential step 40 is to subject both strips simultaneously to a 45 pressing operation in the presence of heat.

The feed and pressure belts.—Both strips 2 and 3 and their respective face sheets *c* and *d* are conjointly fed or rather drawn through a heating box or chamber E by a 50 pair of endless belts F supported one above the other by separate sets of drums 24 and 25, respectively, both belts being tightly stretched on horizontal and parallel lines with only the thickness of the strips separating them. Slack or tension of belts F is 55 regulated by adjusting screws 26 bearing against stiff coiled springs 27 which seat against slidable journal boxes 28. These boxes support the axles of drums 24 and 25 60 at one end of the machine. Upper drums 24 are also mounted on frames 29 slidably supported between uprights 30 of box E and adjustably controlled for vertical movement by lift and set screws 31. The relative distance between the working faces of

the belts may thus be changed to correspond with the thickness of a single strip or two or more strips, and the degree of pressure and grip upon the strip or strips passing between the belts may also be regulated at 70 will to provide a constant and uniform pressure-contact with the facing-sheet until the glue has set and in order that wrinkling of the sheet as it dries and also warping of the board may be prevented. The product is 75 commonly referred to as corrugated board. Belts F may be made of any suitable material adapted to withstand heat and make flat contact, and a metal belt profusely perforated has good heat conducting properties 80 and will give quick and uniform drying results. A metal belt also provides a perfectly smooth and solid backing for pressing and feeding purposes. As a substitute, a wire-mesh belt might be employed to good 85 advantage, as its open meshes will permit the heat to pass therethrough to the paper sheets. It is designed that the sheets shall always travel at the same speed as the belts, but if the strips are in any way retarded 90 and not too tightly held in their travel between belts F, no ill effects will follow as the belts will simply slide over the sheets. Feeding might also continue under restraint and then an ironing, wiping effect 95 would be obtained which might be of advantage, particularly in smoothing and polishing certain grades of papers, and I do not wish to limit myself in this respect.

The heating apparatus.—Box E is 100 inclosed on all sides, the strips entering and leaving through a slot 32 in each end, and a high temperature is maintained within the box by suitable steam pipes or coils 34 longitudinally arranged therein and suitably supported between the layers of each belt F. Strips 2 and 3 must necessarily pass through this heated area while in contact with the hot metal belts F, but drying operations are further expedited by circulating hot air through the open interior of the corrugated strips as well. This is feasible for the reason that the corrugations run transversely of the strips and produce a 105 series of transverse air spaces between the facing sheets and whereby open communication may be established with the interior of box E and horizontal hot air exhaust duct 35 extending lengthwise of box E at 110 one side thereof. A circuitous travel of the hot air from the box chamber through the corrugated strips to duct 35 and back to box E is obtained by a suction fan or blower 36 having pipes 37 and 38 connected therewith and with duct 35 and box E, respectively, said blower being operated by pulley 39 or other suitable power connections. Closed communication between the intake end of duct 35 and the open edges of the strips is also provided for within box E by 115 120 125 130

a pair of angle plates 40 secured to flanges 41 forming part of the duct walls and which plates frictionally engage the inner faces of the meeting spans of belts E at their edges. Plates 40 may be made of spring material or otherwise constructed to yield and their length may be greater or less and not necessarily confined to the stretch of the belts between the drums. Pipe 37 from blower 36 leads into the upper portion of box E but may be entered elsewhere, and the heated air within the box is drawn by suction through the transverse spaces in the strip and between the belts from the left side of box E (see Fig. 4). Belts F are also engaged at this side by plates 40' but these are set apart from the wall of box E to permit free intake of hot air into the strips from both the top and bottom portions of box E. A fresh air intake pipe G having a damper valve g is used to regulate the amount of outside air taken into heating box or drier E, and an exhaust flue H having a damper valve h is placed at the top of box E to carry off moisture. The strips under manufacture are four to five feet wide, and the thickness of the board approximately three-sixteenths of an inch. The cross channels for the air are necessarily very small and I find that quick and uniform drying is best obtained by employing a suction at one edge as shown. One condition to contend with is the continuous introduction of cold air into the drier by the corrugated strips—that is, the cold and moist air confined within the transverse spaces or cross channels, and which is difficult to remove in strips of any great width, excepting by suction as provided for by my construction.

Obviously, a forced circulation of hot air through the interior of the strips by suction will expedite drying operations and produce uniform results, and particularly when two or more strips are superimposed as in this machine. However, single strips may also be more rapidly finished, using a machine constructed as described. In summing up the advantages, it will also be seen that this machine is relatively small for the work to be done and saves valuable floor space in the factory, and being small and a quick drier, economy in operation is also obtained. Finally, the output is greatly increased without adding to the cost (comparing this machine with a machine making a single strip) and less power is also needed to operate the same.

Power connections.—Drums 24 and 25 at the discharge end of box E are rotated at the same speed by gears 41', power being applied to the lower drum shaft by sprocket wheel 42 and a c. in 43 leading to the source of power. A cutting device (not shown) is usually placed at this end of the

machine to cut the strip into predetermined lengths. As in other machines, suitable drive connections are also used for the adhesive-applying rollers 11 and 19, and this may be done by sprocket gears 44 and chains 45 driven from shaft 46 of lower drum 25 at the receiving end of box E.

What I claim is:

1. In a machine for facing corrugated paper, a heating chamber and a pair of superimposed belts mounted therein, and a suction device having communicating ducts alined with said belts at their meeting faces and provided with means engaging the same to cut off communication with the interior of the said chamber, and a return pipe from said suction device to said chamber.

2. In a machine for facing corrugated paper, a pair of heat conducting belts, means to operate said belts under tension, means to adjustably fix said belts at predetermined distances apart at their meeting faces, and means to aline and direct a plurality of corrugated strips and facing-sheets between said belts.

3. In a machine for facing corrugated paper, a heating chamber having an exhaust outlet at one side thereof and provided with a valved fresh air intake and a valved exhaust flue, in combination with an air circulating device connected with said duct and heat circulating devices within said chamber.

4. In a machine for facing corrugated paper, a dual set of rollers to carry corrugated sheets and a dual set of rolls to carry flat facing sheets, paste applying means for each corrugated sheet and rolls through which said several sheets are brought together one upon the other, in combination with a drying chamber, a pair of endless belts therein adapted to receive both said corrugated sheets with their facings between them, and means to dry the stock comprising suction devices and ducts adapted to cause the air to flow transversely through the corrugations of the stock.

5. In a machine for facing corrugated paper, a closed heating chamber having a pair of superimposed belts to feed and press and finish the product and means to guide two faced corrugated strips one upon the other into the said heating chamber between said belts, in combination with a suction device having open communication with the edges of said belts and the corrugated strips between the same.

6. In a machine for facing corrugated paper, a heating chamber and means to feed a plurality of faced corrugated strips and simultaneously through the same one flat upon the other, in combination with a suction device having exhaust connections at one side of said chamber alined with the corresponding edges of said strips, the oppo-

site edges of said strips having open communication with the interior of said heating device.

7. In a machine for facing corrugated paper, a drying chamber having a pair of superimposed endless belts rotatably mounted therein and apart from the walls thereof at their edges, said belts being adapted to convey corrugated strips therethrough, heating means arranged within said chamber, an exhaust duct lengthwise in one side of said chamber opposite the edges of said belts and oppositely arranged metallic plates at both edges of said belts arranged to form hot air ducts to direct the air transversely between said belts.
8. In a machine for facing corrugated paper, a heating chamber having an ex-

haust duct longitudinally thereof at one side and exhaust devices connected with said duct, in combination with a set of feeding and pressing devices for permanently affixing facing-sheets to corrugated strips longitudinally arranged within said chamber and in open alinement with said duct at their edges, and means at the said edges to direct the heated air between the same from one side edge to the other, whereby hot air is drawn through the corrugated strips.

In testimony whereof I affix my signature 30 in the presence of two witnesses.

JOHN N. HAHN.
